DESIGN FOR A DRAWER PULL

Arthur N. Nyquist, Rockford, Ill., assignor to
Anderson Brass Shops, Inc., Rockford, Ill., a
corporation of Illinois

Application October 15, 1936, Serial No. 65,306

Term of patent 3½ years

To all whom it may concern:

Be it known that I, Arthur N. Nyquist, a citizen of the United States, residing at Rockford, in the county of Winnebago and State of Illinois, have invented a new, original, and ornamental Design for a Drawer Pull, of which the following is a specification, reference being had to the accompanying drawing, forming part thereof.

In the drawing, Figure 1 is a plan view of a drawer pull of my new design.

Fig. 2 is a side elevation.

Fig. 3 is an end elevation.

Figs. 4, 5, and 6 are sectional views taken respectively along the lines 4—4, 5—5, and 6—6 of Fig. 1.

I claim:

The ornamental design for a drawer pull, substantially as shown.

ARTHUR N. NYQUIST.
